CLAIM

The ornamental design for container for treating animals, as shown and described.

DESCRIPTION

FIG. 1 is a perspective view of a container for treating animals with the yoke illustrated in an open position, showing my new design, however it is to be noted that the yoke is illustrated in a closed position in all other FIGS. 2 through 7 as follows;
FIG. 2 is a top plan view thereof;
FIG. 3 is a left side elevational view thereof;
FIG. 4 is a bottom plan view thereof;
FIG. 5 is a right side elevational view thereof;
FIG. 6 is a front elevational view thereof; and,
FIG. 7 is a rear elevational view thereof.

FIG. 1**FIG. 2****FIG. 6****FIG. 3****FIG. 4****FIG. 7****FIG. 5**
